ROBERT H. HAZELTINE, OF ITHACA, NEW YORK.

MACHINE FOR RESEATING VALVES.

No. 918,049.

Specification of Letters Patent. Patented April 13, 1909.

Application filed March 26, 1907. Serial No. 364,639.

REISSUED

To all whom it may concern:

Be it known that I, ROBERT H. HAZELTINE, of Ithaca, in the county of Tompkins, in the State of New York, have invented new and 5 useful Improvements in Machines for Reseating Valves, of which the following, taken in connection with the accompanying drawings, is a full, clear, and exact description.

This invention relates to certain improvements in machines for reseating valves and 10 refers more particularly to mechanism for rotating the valve through limited arcs in reverse directions upon its seat using an interposed polishing or grinding element such 15 as flour of emery and oil, pumice stone or other polishing paste or fine abrasive for simultaneously grinding the valve and its seat into exact conformity with each other without liability of cutting or channeling 20 such valve or seat.

My object is to provide simple practical and efficient mechanism adapted to be operated by hand and by which the valve may be rotated through limited arcs, in opposite directions and intermittently and automatically moved into and out of contact with its seat at regular predetermined intervals.

One of the more specific objects is to provide a simple means for holding the valve 25 during its partial rotation and intermittent elevation and depression.

Another specific object is to arrange the valve holder so as to be readily inserted into the valve chamber through the same opening 35 through which the valve is adapted to be inserted and removed.

A still further object is to arrange the pressure devices by which the valve is held to its seat so that the line of pressure is co-40 axial with the valve.

Another object is to associate with the driven pinion, which rotates the valve holder, two opposed driving gears adapted 45 to be operated by hand and each mutilated in such manner that the valve holder will be rotated through limited arcs in one direction by one gear and then similarly rotated in the opposite direction through a corresponding arc by the other gear.

50 Another object is to provide one of the gears and the driven shaft for the valve holder with co-acting elements for intermit-

tingly raising and lowering the valve from and to its seat.

Other objects and uses will be brought out 55 in the following description.

In the drawings—Figure 1 is a side elevation of a valve reseating device embodying the various features of my invention, a portion of the gear nearest to the point of view 60 being broken away to show the mutilated teeth of the opposite gear. Fig. 2 is an opposite face view of the same device except that the gear nearest to the point of view is removed. Fig. 3 is a vertical sectional view 65 taken on line —3—, Fig. 1. Fig. 4 is a sectional view taken on line 4—4, Fig. 3.

While this machine is specially designed to fit the valves as —a— upon the seats as —b— of gas engines, pumps and the like, it 70 is equally applicable for refitting any puppet or lift valve to its seat and comprises essentially a valve holder —1— mounted upon a rotary axially movable shaft —2— which is journaled in suitable bearings —3— and is 75 adapted to be rotated by means of a pinion —4— and suitable mutilated driving gears —5— and —6—. These gears —5— and —6— are keyed to a rotary shaft —7— which is journaled in a bearing —8— of a 80 suitable supporting frame or standard —9— terminating in a suitable hand piece —10—, the lower end of said frame being extended downwardly between the gears —5— and —6— and connected to the bearing —3— by 85 means of a yoke —11—, said yoke connecting the bearings —3— and —8— and holding them in fixed relation to each other.

The particular type of valve —a— shown in the drawings is usually provided with a slot —12— and with a convex upper face through which the slot extends and in order to adapt the holder to retain this particular form of valve, said holder is provided with a central projection —13— and a concave 95 lower face —14— the projection —13— serving to enter the slot to cause the valve —a— to rotate therewith while the concave lower face of the holder —1— is made to conform to the convexity of the upper face 100 of the valve so as to properly center said valve on its seat and at the same time afford ample bearing to prevent lateral vibration of the valve during the reseating operation.

The projection —13— is tapered slightly so as to wedge into the slot and thereby frictionally hold the valve during the intermittent elevation and depression of the holder as will be presently described but in addition to this means of holding the valve, I preferably make the holder of magnetizable metal adapted to attract and to hold the valve, which is usually made of iron, by 5 magnetic attraction, said holder constituting an electro-magnet having a suitable winding —15— of wire adapted to be connected to any source of electric energy as a battery —16— and switch —17— shown diagrammatically in Fig. 1.

The vertical shaft —2— extends downwardly some distance beyond the bearing —3— and into the holder —1— to which it is secured by a suitable key or pin —18— to 20 cause the holder to rotate with the shaft, suitable space or clearance being left between the top of the holder and under side of the bearing —3— to permit limited vertical movement of the holder.

25 The holder —1— is provided with a central lengthwise socket —19— open at the top and terminating some distance above the bottom for receiving one end of a spring —20— the lower end of said spring bearing upon 30 the lower side of the socket while its upper end bears upon the upper side of the bearing —3— or rather a suitable bushing —21— constituting a part of the bearing but it is preferably screw threaded and engaged with 35 the hub as —22— of the pinion —4— to lock said pinion against endwise movement and still form a bearing for the shaft —2—.

The pinion —4— is feathered by suitable key —23— to the shaft —2— to move end- 40 wise therethrough, the hub of said pinion being journaled in the upper end of the bearing —3— and is adapted to mesh with the opposed gears —5— and —6— which are adapted to be rotated simultaneously by 45 means of a hand piece —24— on the gear —5— as best seen in Figs. 1 and 3. These gears —5— and —6— are mutilated in such manner as to alternately rotate the valve holder —1— in reverse directions through 50 approximately 90° or a quarter turn but under a comparatively high rate of speed during the continued rotation of the gears —5— and —6— in the same direction and for this purpose the teeth of similar segmental parts 55 of each gear are removed or rather alternate with similar segmental parts of each gear with teeth adapted to engage and rotate the pinion —4—, shaft —2— and holder —1— through substantially a quarter revolution, 60 the toothed segments of one gear being opposite the mutilated segments of the other gear so that when one set of teeth of one gear are in mesh with the pinion, the toothed segments of the other gear are out of mesh with

said pinion so that the pinion is alternately 65 rotated a quarter turn in reverse directions.

The gears —5— and —6— are necessarily of the same pitch diameter and considerably larger than the pinion —4— and therefore each gear is provided with a series of 70 toothed segments and mutilated segments alternating with each other, the toothed segment being of substantially the same circumferential length as the mutilated segment so as soon as the mutilated segments 75 of one gear are presented to the pinion, the toothed segments of the other gear engage and rotate the pinion in the reverse direction. During this rotation of the valve holder —1— which is pressed downwardly 80 by the spring —20—, the valve is held under tension of the spring against its seat and the reverse rotation of said valve through limited arcs as previously described causes a more uniform grinding or polishing of 85 the valve and its seat so that they will exactly fit each other, it being understood that a suitable abrasive or polishing material as flour of emery and oil or equivalent grinding material is interposed between the valve 90 and its seat during the operation of grinding.

During the rotation of the valve in reverse directions, it is desirable to intermittently elevate and depress the valve from 95 and to its seat so as to avoid excessive wear or channeling in one place by foreign matter and for this purpose I provide the gear —5— with a cam —25— which is adapted to engage a roller bearing —26— on the upper 100 end of the shaft —2— at each revolution of the gears —5— and —6— whereby the shaft and its holder —1— together with the valve —9— is elevated against the action of the spring —20— which as soon as the cam 105 —25— passes the roller bearing —26— depresses the holder —1— and thereby arranges the valve with its seat without break in the continuity of the gears —5— and —6—.

The operation of my invention is as follows: The operator places the valve —a— against the holder —1— which retains it in place by means of the wedge fit between the projection —13— and slot —12— and also by magnetic attraction due to the energizing of the core constituting the holder —1— whereupon the gears —5— and —6— are rotated by means of the hand piece —24—, the whole device being supported by the bearing —3— upon any suitable support, 115 not shown, with the valve —a— against its seat —b— when the spring —20— is dis tended. During the rotation of the gears —5— and —6—, the pinion —4—, shaft —5— and valve holder —1— together with 120 the valve —a— will be rotated alternately a quarter of a turn in reverse directions by the alternating toothed segments of said gears 125

and at each revolution of the latter, the shaft —2— carrying the holder —1— and valve —a— will be temporarily elevated by the cam —25— and instantly depressed by the spring —20— to arrange the valve with its seat as soon as the cam —25— passes the roller bearing —26—, this action being repeated until the valve and the seat are properly ground to establish a perfect fit with each other whereupon the apparatus may be removed and the valve detached and re-applied to its seat for further use.

One or more of the toothed segments and blank spaces of each mutilated gear are of greater or less arc than the remaining segments; that is, two or more consecutive toothed segments may have a progressively increasing or decreasing number of teeth, the object of which is to rotate the valve through unequal arcs during succeeding reversals in the direction of rotation to prevent contact of the same parts of the valve and seat with each other upon such reversal of movement. It is obvious that this variation in the arc of movement and consequent change in the contacting surfaces of the valve and seat may be effected by various means than that hereinbefore described, and applicant does not herein limit himself to the exact mechanism shown and described.

The support for the roller bearing —26— is held against rotation by an arm —30— having a groove —31— riding upon a rib —32— on one side of the yoke —11—, said support having a collar —33— and provided with a screw —34— which enters a groove —35— in the shaft —2— so as to permit the rotation of the shaft in the hub or sleeve —33— and at the same time to afford means whereby the hub —33— and its arm —30— are moved vertically with the shaft.

What I claim is:

1. A valve reseating device comprising a rotary electromagnetic valve holder, and mechanism for rotating the valve holder in reverse directions by the continued movement of said driving mechanism in the same direction, and means brought into action by the driving mechanism for intermittently elevating the valve holder.

2. A valve reseating device comprising a rotary electromagnetic valve holder, and driving means therefor including a pair of mutilated gears acting alternately to rotate the holder in reverse directions by continued movement of the gears in the same direction, and means brought into action by the rotation of one of the gears for intermittently elevating the valve holder.

3. A machine for reseating valves comprising a rotary electromagnetic valve holder and driving means therefor including mechanism for rotating the valve through unequal arcs in reverse directions.

4. A hand operated reseating mechanism comprising a frame having a hand piece at one end, and a valve holding device rotatably mounted in its opposite end, a shaft journaled in the frame between the hand piece and rotary valve holder, a pinion mounted in the frame between the valve holder and shaft for rotating the valve holder, a gear mounted on the shaft and meshing with said pinion and provided with a hand piece whereby it may be rotated, and means actuated by the gear for elevating the valve holder once in each revolution of said gear.

5. A hand operated reseating mechanism comprising a frame having a hand piece at one end, and a valve holding device rotatably mounted in its opposite end, a shaft journaled in the frame between the hand piece and rotary valve holder, a pinion mounted in the frame between the valve holder and shaft for rotating the valve holder, a gear mounted on the shaft and meshing with said pinion and provided with a hand piece whereby it may be rotated, means actuated by the gear for elevating the valve holder once in each revolution of said gear, and a spring for depressing the valve holder after each elevation by said means.

6. In a hand operated valve reseating device, the combination of a frame having a hand piece at one end, an axially movable rotatable shaft journaled in the opposite end of the frame, a tool holder secured to said shaft and movable axially therewith, a pinion journaled in said opposite end of the frame and feathered upon said shaft to permit the shaft to move axially therethrough, a driving shaft journaled in the frame between the pinion and hand piece, a gear secured to the shaft and meshing with said pinion to rotate the latter and also the first named shaft, means actuated by the gear for moving the shaft endwise in one direction at each revolution of the gear, and a spring for moving said first named shaft in the opposite direction when released by said means.

7. A hand operated valve reseating device comprising a frame having a hand piece at one end, a rotary tool holder journaled in the opposite end of the frame, a pinion for rotating said tool holder, a shaft journaled in the frame between the pinion and hand piece, and a pair of mutilated gears secured to said shaft and alternately engaging opposite sides of the pinion, one of said gears being provided with a hand piece by which the shaft and both gears may be rotated, means actuated by one of the gears for moving the tool holder axially in one direction, and a spring for moving the tool holder in the opposite direction when released by said means.

8. A machine for reseating valves, comprising means for reciprocating the valve, and means for periodically rotating the valve

through a greater arc in one direction than in the other direction, thereby progressively advancing the valve on its seat.

9. In a machine for reseating valves, the combination of means for imparting a reciprocating rotary motion to the valve, and means for periodically advancing the valve through a greater arc in one direction than in the opposite direction, thereby progressively rotating the valve on its seat.

10. In a machine for reseating valves, the combination of means for alternately rotat-

ing the valve in opposite directions on its seat, and means for periodically advancing the valve in one direction, thereby progressively changing the position of the valve relative to its seat. ¹⁵

In witness whereof I have hereunto set my hand this 20th day of March 1907.

ROBERT H. HAZELTINE.
